UNITED STATES PATENT OFFICE.

HERBERT R. McCUNE, OF DECATUR, ILLINOIS, ASSIGNEE TO DECATUR BRICK MFG. CO., OF DECATUR, ILLINOIS, A CORPORATION OF ILLINOIS.

BRICK MACHINE.

Application filed August 5, 1926. Serial No. 127,234.

This invention has reference to certain new and useful improvements in brick machines and pertains more particularly to a brick machine for ornamenting the surface 5 or surfaces of the brick.

The principal object of the invention is to provide a brick machine which has novel and improved means for ornamenting the surface of the brick by roughening same, and 10 more especially to pick out particles of the clay by means of a device which latter is positively rotated during the feeding and pressing of the clay and which carries a plurality of picking elements themselves bodily 15 movable with the device, but capable of rotation or movement independently of the device.

A further object of the invention is to provide a device of this character which may 20 be easily applied to existing types of brick machines and properly adjusted relative thereto.

That the invention may be more fully understood, reference is had to the accompanying drawings forming a part of the present description and illustrating a preferred embodiment of the invention, in which:

Figure 1 is a top plan view of the invention applied to a brick machine, the latter 30 shown in fragment;

Figure 2 is a side elevation;

Figure 3 is a front elevation, parts being omitted;

Figure 4 is a detail view of one of the 35 picking devices;

Figure 5 is a longitudinal sectional view of Figure 4;

Figure 6 is a detail view of one of the 40 picker carrying shafts;

Figure 7 is a fragmentary view, partly in section of a modified form of picker device;

Figure 8 is a detail side elevational view 45 partly in section of one of the picker members;

Figure 9 is a front elevation of Figure 8;

Figure 10 is a side elevation, partly broken away of a further modified form of picker device, and

50 Figure 11 is a longitudinal sectional view of Figure 10.

Like characters of reference denote corresponding parts throughout the figures.

In proceeding in accordance with the pres-

ent invention, 1 indicates the mouth and die 55 of a press of standard manufacture.

The mechanism embodying my invention is supported therefrom by means of the arms or bracket members 2, and includes the horizontal supporting bar 3 and the vertically 60 extending bracket members 4 movable on said bar, these elements forming the supporting frame of the mechanism. The supporting bar 3 is connected to a plurality of the arms or bracket members 2, and other of 65 the arms or bracket members 2 are connected to the lower portions of the vertically extending bracket members 4, so that the frame is supported from the press.

This frame forms the supporting means 70 for a pair of ornamenting means for the sides of the column of clay, as it passes from the die to the usual conveyer mechanism. As stated hereinbefore, the vertical bracket members 4 are movable on the horizontal 75 supporting bar 3, being provided with the apertures 5, through which bar 3 passes, set screws 6 being provided for locking or holding the parts in adjusted position. These vertical bracket members 4 also have the 80 journal openings 7. The hub portions 8 of gears 9 bear against the vertical bracket members 4, these gears being slidably keyed, by means of a long key-way 10, to the horizontally 85 extending operating shaft 11. This shaft 11 extends beyond the supporting frame and has connected thereto the sprocket 12, which is driven by chain or other flexible connection 13 from driving sprocket 14, which is operatively connected to the conveyer 90 mechanism as shown.

Secured to the top of each bracket member 4 is the bracket 15 through which passes the adjusting or tension screw 16 which has a right hand thread on one side and a left hand thread on the other side, for the purpose of making close and minute adjustments. The holding member 17 is secured to the supporting bar 3 by means of set screws 18 and is provided with the bifurcated or forked portion 19 which fits between the collars 20 on the shaft 11, so as to hold the shaft rigid.

Each of the vertically extending bracket members is provided with the lateral extension 21, bored as at 22 to provide a bearing for the vertical shaft 23, this shaft having a gear 24 on its upper end in mesh with

gear 9 on horizontal shaft 11. Secured to the lower end of each vertically extending bracket member 4 is the horizontally extending plate member 25, which is formed with the aperture 26 opening through the bottom thereof. This aperture receives the journal extension 28 of bearing plate 29, which is adjusted in position by means of the screws 30, the journal extension 28 providing a journal for the lower end of the vertical shaft 23, which is provided with the grease cup and oil way 27.

Brackets 31 adjustably mounted on each side of the frame by the nut and screw connection with the flange, as shown, extend upwardly from the conveyer frame and have T-heads to support the bearing for the horizontal shaft 32, this shaft being positioned forwardly of said last described mechanism. Additional braces 31' extend to the frame where they are adjustably connected by the slot and bolt connection 31''. This horizontal shaft is provided with the driving sprocket 33 on the other side, which is driven by the chain or other flexible connection from the sprocket 34 on the other side of shaft 11. This shaft 32 has the means described on each side to permit raising and lowering.

The shaft 32 and also the shafts 23 each have rigidly secured thereon, heads or disks 40, which latter are spaced and receive in such space a series of shafts 41, the latter being reduced at their ends at 43 and received in perforations provided therefor in the disks. Each shaft 41 is provided with radial threaded openings in which the inner ends of picker elements 44 are threaded, lock nuts 45 being employed to rigidly secure the picker elements to the shaft. The shafts 41 are rotatable independently of the disks 40 whereby it will be seen that while pickers 44 are bodily carried with the heads 40, still same can rotate or move independently of the heads, which effects a varying picking or digging action in the body of clay.

In Figures 7, 8 and 9 of the drawings a modified form of the invention is disclosed wherein the shaft 50 of the picker device 50 has a series of shafts 51 secured to heads 52, but one of the latter being shown. As shown in Figures 8 and 9, hubs 53 are provided which freely rotate on the shaft 51 and which are provided with radial threaded openings threadedly receiving the picker elements 54 which latter are held by lock nuts 55 onto the hubs. Other hubs 56 are loosely mounted on the shafts 51 and are provided with picker blades 57 which extend radially and which are set at an angle to the axes of the shafts 51. It will be noted that in this form of the invention the picker elements 54 alternate with the picker blades 57. The blades 57 of each hub 56 are relatively staggered, to thus produce a corre-

sponding effect in roughening of the surface of the brick.

In Figures 10 and 11, a still further modified form of the invention is disclosed and wherein the picker devices are formed in their entirety of blades 60 of relative staggered form mounted on hubs 61, the latter being freely rotatable on shafts 62, carried by heads 63 on the shaft 64. In this form of the invention it will be seen that the picker blades 60 are like the blades 57 of Figure 7; Figures 10 and 11 disclosing the picker device as composed entirely of blade pickers as distinguished from Figure 7 wherein the blade pickers alternate with tooth pickers 54.

In operation, the column of clay is forced out of the press and is subject to the action of the picker devices on the opposite sides and top thereof, the picker devices being rotated in a direction opposite to that in which the clay moves. The picker devices in each form of the invention are positively and bodily moved with respect to the body of clay, but it will be noted that the pickers themselves can rotate independently of the body rotation of the picker device, which thus produces varying effects which are exceedingly ornamental and attractive.

The invention thus affords a compound movement of the pickers, or ornamenting devices, which latter are bodily rotated and at the same time upon entering the clay, move independently of the devices themselves, to provide a dragging action of the pickers, and thus produce varying effects, as distinguished from a set or regular effect.

What I claim is:—

1. An ornamenting attachment for brick machines, including supporting means, a rotatable picker device, means to mount the pickers for rotary movement independent of movement of the device, and means to positively rotate the device. 105

2. An ornamenting attachment for brick machines, including a supporting means, a movable picker device, means to mount the pickers for movement independent of movement of the device, and means to effect movement of the device. 110

3. An ornamenting attachment for brick machines, including a supporting means, a bodily rotatable picker device, circular series of pickers carried by the device, means to mount the pickers for movement independent of the device, and means to rotate the device. 115

4. An ornamenting attachment for brick machines, including a supporting means, a movable carrier, ornamenting means on the carrier, means to mount the ornamenting means for movement independent of the carrier, and means to effect movement of the carrier. 125

5. An ornamenting attachment for brick

machines, including a supporting means, brick ornamenting means on the support, and means whereby to impart a compound movement to the ornamenting means.

5 6. An ornamenting attachment for brick machines, including a supporting means, a cylindrical picker device, a series of pickers arranged in circular formation on the device, means to rotate the device, and means 10 to permit of independent rotary movement of the pickers with respect to the device.

7. In an ornamenting device for bricks, ornamenting means, means to effect bodily movement of the ornamenting means, and means to permit movement of the ornamenting means independently of the first named movement thereof.

8. An ornamenting device for brick machines, including a carrier composed of 20 spaced heads, means for rotating the carrier, shafts connecting the heads, and means on the shafts engageable with the bricks and movable independently of the heads to ornament the bricks.

25 9. An ornamenting device for brick machines, including a rotatable carrier, means to rotate the carrier, and means engageable

with the bricks and movable thereby independently of the carrier to ornament the bricks.

30

10. An ornamenting device for brick machines, including a carrier having shafts thereon, means to rotate the carrier and circular series of pickers carried by the shafts for bodily movement with the carrier and 35 for movement independent thereof to ornament the bricks.

11. In a brick machine, means for forcing a column of clay out of the machine, a rotatable carrier, ornamenting means on the 40 carrier for engaging and ornamenting the column of clay, means to rotate the carrier and therewith the ornamenting means in a direction opposite to the direction of movement of the column of clay, and means to 45 permit movement of the ornamenting means independent of the movement of the carrier so as to cause the ornamenting means upon engagement with the column of clay to move with and thereby in the direction 50 of movement of the column of clay.

In witness whereof, I have hereunto affixed my hand this 13th day of July, 1926.

HERBERT R. McCUNE.
